VIBRATOR

Henry M. Dressel, Oak Park, Ill., assignor to Oak
Manufacturing Company, Chicago, Ill., a cor-
poration of Illinois

Application July 25, 1935, Serial No. 32,989

4 Claims. (Cl. 175—373)

This invention relates to vibrators primarily for use in connection with automobile radios wherein the low voltage storage battery current is rapidly interrupted and thereafter converted to high voltage. An object of this invention is to devise a vibrator which will be simple, cheap and be adapted to operate for long periods of time without attention. A further object is to devise a vibrator which will operate without substantial arcing at the contacts and which will be independent of the transformer with which such vibrator customarily operates. Other and additional objects will be apparent as the description proceeds.

15 In the drawing, Fig. 1 is a diagrammatic representation of the invention.

This structure is diagrammatically shown and may have as one physical embodiment thereof the structure shown in my application Serial No. 758,924, filed December 24, 1934. In the drawing a reed 1 rigidly mounted at one end 2 carries an armature 3 at the free end thereof. Reed 1 carries a driving contact 5 and an additional circuit contact 6. Disposed on opposite sides of the contact 6 are a pair of fixed contacts 8 and 9 with which contact 6 is adapted to alternately cooperate during the normal operation of the device. An additional fixed contact 10 is provided to cooperate with driving contact 5.

30 Cooperatively associated with armature 3 is a pole piece 12 of a suitable magnetic field structure. A pair of windings 14 and 15 are adapted to energize magnetic field structure 12 as hereinafter described. These windings are preferably of equal and opposite magnetizing effects and may otherwise be disposed in any suitable manner.

35 Winding 14 has one terminal connected to fixed driving contact 10 and the other terminal connected to junction point 17 on the line 18. Winding 15 has one terminal connected by means of a wire 19 to reed 1 while the other terminal is connected by conductor 18 to line 20 leading to one terminal of a battery 21. The other terminal of battery 21 is connected to reed 1. Line 20 is connected to the mid-point 22 of a pair of primary windings 23 and 24 of a transformer 25 having a secondary 26. The outer terminals of primary windings 23 and 24 are connected to fixed contacts 8 and 9 respectively.

40 In its rest position, reed 1 is symmetrically disposed between fixed contacts 8 and 9 with the driving contacts open. Assuming the battery circuit closed (the control of this circuit may be effected by any suitable switching mechanism

not shown) winding 15 will be energized by battery 21. This will cause armature 3 to be attracted to close driving contacts 5 and 10 and circuit contacts 6 and 8. As soon as contacts 5 and 10 are closed, winding 14 will be energized 5 and neutralize the magnetizing effect of winding 15. Armature 3 will be released and the reed will swing over to its other extreme position closing contacts 6 and 9 and permit the continuous current through winding 15 to again exert its 10 magnetizing effort. In this way windings 23 and 24 will be alternately energized.

It is clear that any potentials in primary windings 23 and 24 howsoever created will not be able in any way to affect either of the windings 14 or 15 of the vibrator. Furthermore, when the reed is just opening driving contacts 5 and 10, the low resistance of battery 21 in comparison to the resistance of winding 15 will permit winding 15 in effect to function as a short circuited secondary and reduce arcing at contacts 5 and 10.

If windings 14 and 15 are of equal size wire and wound in bifilar relationship substantially the same effect will be obtained as is present in my Patent 2,012,123. This effect in brief is a 25 high starting torque without excessive amplitude of vibration of the reed occasioned by the running losses during the operation of the vibrator.

Having described my invention what I claim is as follows:

1. A vibrator comprising a magnetizing member having an active pole face, a reed rigidly supported at one end having an armature at the other end and adapted to vibrate in front of said pole face, a driving contact mounted on said reed, a stationary contact cooperating with said driving contact in the attracted position thereof, a pair of magnetizing windings for said magnetic structure, a connection from said stationary contact to one terminal of one coil, a connection 40 from one terminal of the other coil to said reed, said reed constituting one terminal of the vibrator, and a connection between the other ends of said two coils, said connection constituting the other terminal of said vibrator, said coils being 45 so wound as to have equal and opposite magnetizing effects.

2. The structure of claim 1 wherein said two magnetizing coils are wound in bifilar relationship.

3. A vibrator comprising a magnetizing structure having an active pole face, a reed rigidly supported at one end having an armature at the other end and adapted to vibrate in front of said pole face, a pair of magnetizing windings, 55

a driving contact on said reed, an additional contact carried by said reed, a stationary contact cooperating with said driving contact in the attracted position of the reed, stationary contacts 5 cooperating with said additional reed contact in each of the two extreme reed positions, a connection from said stationary driving contact to one terminal of one coil, a connection from a terminal of the other coil to said reed, said reed 10 comprising one of the energizing terminals for said vibrator, a connection between each remain-

ing terminal of said two coils, said connection serving as the other energizing terminal for said vibrator, and connections from said stationary contacts cooperating with said additional reed contact, said connections together with said reed 5 constituting the three terminals of a load circuit.

4. The structure of claim 3 wherein said two windings are wound in bifilar relationship.
